UNITED STATES PATENT OFFICE

132,712

DESIGN FOR A MAINTENANCE SERVICE TRUCK

Herman J. Troche, Cleveland Heights, and James H. Holan, Jr., Lakewood, Ohio, assignors to The American Coach & Body Company, Cleveland, Ohio, a corporation of Ohio

Application April 4, 1942, Serial No. 106,458

Term of patent 14 years

To all whom it may concern:

Be it known that we, Herman J. Troche and James H. Holan, Jr., citizens of the United States of America, residing at Cleveland Heights and Lakewood, respectively, both in the county of Cuyahoga, State of Ohio, having invented a new, original, and ornamental Design for a Maintenance Service Truck, of which the following is a specification, reference being had to the accompanying drawings, forming part thereof.

In the drawings:

Fig. 1 is a side perspective view of a maintenance service truck showing our new design;

Fig. 2 is a rear perspective view;

Fig. 3 is a side perspective view; and
Fig. 4 is a rear elevational view.

In the drawings, Figs. 1 and 2 show how the truck appears with the canopy in the extended position while Figs. 3 and 4 show the appearance of the truck with the canopy closed.

The dominant features of the design reside in the portions shown in full lines.

We claim:

The ornamental design for a maintenance service truck, substantially as shown and described.

HERMAN J. TROCHE.
JAMES H. HOLAN, JR.
